UNITED STATES PATENT OFFICE.

HEINRICH BECK, OF SCHENECTADY, NEW YORK.

TOY GUN.

1,266,533.

Specification of Letters Patent. Patented May 14, 1918.

Application filed November 5, 1917. Serial No. 200,400.

To all whom it may concern:

Be it known that I, HEINRICH BECK, a subject of the Emperor of Germany, residing at 1206 Union street, Schenectady, in the 5 county of Schenectady and State of New York, have invented new and useful Improvements in Toy Guns, of which the following is a specification.

This invention relates to toy guns, particularly that class of guns which throw missiles prepared by the gun itself from flat pieces or strips of soft material, and which are projected by compressed air.

Such missiles are preferably cut from 15 fruit skins or peels, such for instance, as orange peels or the like, but finely cut flat apple or potato slices may also be used advantageously as well as plates or strips of any suitable manufactured material conveniently prepared to have similar properties or qualities of said peels or slices.

One very important advantage of such missiles is their softness which will prevent injuries, for instance, to the eyes, etc., in case 25 the missiles are carelessly shot or thrown.

In the accompanying drawings:—

Figure 1 shows a toy gun constructed according to the present invention.

Fig. 2 is a similar view of a modified 30 form of gun.

Fig. 3 shows a modification of the gun shown in Fig. 1.

Fig. 4 is a further modified form of the gun.

Fig. 5 shows another modification.

Fig. 6 is a still further modification.

Fig. 7 shows another modified form of the gun.

Fig. 8 is a further modification of the gun.

Fig. 9 is another modification.

Fig. 10 shows a toy gun according to the present invention, in the form of a rapid firer.

Fig. 11 is a section on line a—b of Fig. 10.

As illustrated in Fig. 1, the missile or ammunition 4 is cylindrical and is secured within a holder 3, while the ejector rod 2 slides within a guide socket 3^a with its axis in true alinement with the axis of the barrel 1.

If the ejector rod is pushed into the barrel by means of any suitable well-known elements, it will cut out of the material a piece which has a diameter equal to the diameter of the barrel and which will be pushed forward by said rod within the barrel toward a

similar missile previously cut out which then is ejected in the well-known manner by the air compressed between both missiles during the forwarding motion of the ejector rod. In order to increase the compression it is 60 advisable to somewhat reduce the mouth of the barrel.

This construction, however, shows the defect that missiles cut out of soft material, such as, for instance, orange peels will not 65 establish or constitute a tightly fitting piston within the barrel and it will consequently not be possible to produce any noticeable amount of compression.

This disadvantage is overcome in the 70 modified form of gun illustrated in Fig. 2 in which the barrel 1 slides within a guide sleeve 3^a and has a somewhat larger diameter at its front end than at its rear. If the barrel 1 is pushed forward by means of the 75 knob or handle 5 it will cut out a missile from the strip of material 4 inserted for this purpose into the holder 3, which is larger than the compression chamber within the barrel. If now the ejector rod 2 is pushed 80 forward in any well-known manner or by any suitable well-known device, the missile will in time be pressed into the barrel and will form therein a tightly fitting piston allowing the formation of a cushion of ex- 85 tremely high compressed air behind the first missile and in front of the second missile formed by the plunger or ejector when the same is pushed forward into the barrel. Also, in this construction, it is well to some- 90 what reduce the outer end of the barrel. The ejector rod can be made of such a length that when pressed into the barrel it reaches into the reduced portion of the same. Mechanical connections of any well-known pat- 95 tern may be provided between the ejector rod and barrel and also the strip of material, so that the operation of one will also actuate the other elements.

In the modified form of gun shown in Fig. 100 3 the missile 4 is pressed into the barrel 1 by the operation of a part 8, which part in the gun illustrated in Fig. 4 also stamps the missile from the material and presses the same into the barrel.

Fig. 5 shows a modification of the gun built according to the same principle as the gun shown in Fig. 4, with the exception that the movement of the part 8 is transmitted through the ejector rod 2. After the mis- 110

sile has been stamped from the material, the lever 9 will strike against the part 10 and allow a free movement of the ejector rod.

The modified form of gun illustrated in Fig. 6 is intended for the same purpose but the ejector rod 2 is sliding within the part 8 and cannot turn with the same. If the ejector rod 2 is rotated, the part 8 will participate in said rotation. This part 8 is guided within an inclined slot 11 and consequently its rotation will also produce a movement toward the front which will effect the cutting of the missiles from the material. The ejector is then pushed forward in the well-known manner.

In the modified form of gun according to Fig. 7, the part 3 is made of two parts adapted to be folded around or over the axle 12 and the missile is cut out of the material 4 by folding both parts over said axle.

The modified form illustrated in Fig. 9 shows a gun in which every piece cut out of the material presents the appearance of a missile while a piston 15 within a compression chamber 16 is used for producing the air compression. The barrel 1 is preferably cylindrical and the diameter of the missile is somewhat larger than the diameter of the barrel. Between the barrel and the compression chamber a suitable packing is interposed. The barrel is retracted by means of the rotation of the knob or handle 5, and will thus cut out the missile from the material while the end of the barrel is pressed against the part 3 which is provided with a suitable washer or packing. As shown in Fig. 9, the barrel is retracted by a separate device and the strip of material 4 for the ammunition constitutes the packing. In the form of gun illustrated in Fig. 10 the barrel 1 is also retracted and a conical body 17 enters the barrel after the missile has been cut out from the strip of material. The missile will thereby be pressed into the cylindrical body of the barrel and present a tight fitting. Moreover, a special washer or packing 18 can also be used. It will be clear that the barrel can also be made stationary while a movable part, such for instance as a body 50 as shown in Fig. 4, can be moved against the barrel. Any mechanical connections of a suitable pattern may be provided to connect the piston and barrel allowing independent motion of both.

55 As illustrated in Fig. 10, the part 19 secured to the ejector 20 and trigger 21 is firmly connected by means of a rod 22 with the barrel 1. The part 19 slides within the barrel and can be moved by means of the 60 knob 5 so far toward the front that the left-hand end of the barrel is engaging the bushing 3^b and the strip of material 4 can now be moved by hand or mechanically for one step by means of the knob 5. If said knob 65 is then retracted the barrel will be moved

backward and will cut out the ammunition. Simultaneously, the spring 23 behind the piston will be tensioned. By a turn of the handle 5 the part 19 will be retained in its position. By the operation of the trigger 70 21 the piston 15 is pushed to the front and will eject the projectile. During the tensioning operation, air is entering the compression chamber through a hole 30, or the piston is so constructed that it is only tight 75 toward one side, so that air can enter the compression chamber on the other side.

Fig. 11 shows a modified form of the gun in the form of a rapid firer. The barrel 1 and the ejector 2 are connected by means of 80 a link 24. During the retraction of the ejector rod 2 the barrel 1 is also retracted and cuts a projectile from the strip of material 4. The operator operates with his right hand the ejector rod 2 while with his 85 left he advances the strip of material. It is essential that the gun be stationary during these operations and a screw clamp 25, 26 is provided for this purpose allowing a clamping of the gun to a table, etc. The spring 90 29 is provided for assisting in the displacement of the strip of material by holding the barrel toward the front. By suitable mechanical connections, the strip of material can be coupled with the ejector, or with the 95 barrel.

The holes in the strip of material from which the ammunition or projectiles have been cut, are adapted to be engaged by the means for advancing said strip.

The holder 3 for the ammunition is secured, as shown, to a toothed segment 26' adapted to coöperate with a pin 27 arranged to be actuated for the operation of said segment upon the rotation of a vertical shaft 31 105 106 by means of the hand or thumb screw 25 for rotating the gun barrel.

Having thus described my invention, what I claim is:—

1. A toy gun comprising a barrel, a loose 110 plunger for the same, a support for a supply of substantially flat ammunition material, and means for shaping projectiles from the material and for forcing them successively into the barrel; whereby the advance projectile is expelled by the air compressed by the succeeding one.

2. A toy gun comprising a barrel, a plunger for the same, a means for supporting a supply of ammunition material, means for 120 shaping projectiles from said material, and means for compressing the projectile cut from said ammunition supply for ejection from the barrel, substantially as described.

3. A toy gun of the character described, 125 comprising in combination with its barrel, a holder, a supply of ammunition in said holder, and means adapted to be displaced into said barrel after cutting a missile from said ammunition supply.

4. A toy gun of the character described, comprising in combination with its barrel, a holder, a supply of ammunition in said holder consisting of a strip from which the 5 missiles are to be cut, and an ejector rod adapted to be displaced into said barrel after cutting a missile from said ammunition supply.
5. A toy gun of the character described, 10 comprising in combination with its barrel, ejector and ammunition supply, a holder for said supply, means for cutting a missile from said supply, mechanically operated coupling means for operatively connecting said bar-
- rel, ejector and ammunition supply, means 15 for securing the gun to a support, and means for operating the gun to allow its discharge in all directions, substantially as described.
6. A toy gun comprising in combination with its barrel having a reduced discharge 20 and a widened charge end, a means for supplying ammunition to said barrel, a means for cutting a missile from said ammunition supply, a means for ejecting said missile from said barrel, and a support for a supply 25 of such ammunition material.

HEINRICH BECK.
